UNITED STATES PATENT OFFICE.

WILLARD F. RICHARDS, OF BUFFALO, NEW YORK, ASSIGNOR TO THE GOULD COUPLER COMPANY, OF NEW YORK, N. Y.

DESIGN FOR A SIDE FRAME FOR CAR-TRUCKS.

SPECIFICATION forming part of Design No. 26,903, dated April 13, 1897.

Application filed February 27, 1897. Serial No. 625,420. Term of patent 14 years.

To all whom it may concern:

Be it known that I, WILLARD F. RICHARDS, a citizen of the United States, residing at Buffalo, in the county of Erie and State of New York, have invented and produced a new and original Design for Side Frames for Car-Trucks, of which the following is a specification, reference being had to the accompanying drawings, forming a part thereof.

This design relates to the shape or configuration of the side frame of a car-truck, more particularly of a freight-car truck.

In the accompanying drawings, Figure 1 is an elevation of the outer or front side of a side frame embodying my design. Fig. 2 is an elevation of the inner or rear side thereof. Fig. 3 is a top plan view of the same. Figs. 4 and 5 are vertical cross-sections in lines 4 and 5, Fig. 1, respectively.

Like letters of reference refer to like parts in the several figures.

The leading feature of my design consists of a rectangular panel arranged in the middle of the side frame, rectangular horizontal lugs or extensions arranged at the ends of the frame, and a pair of outwardly-converging bars arranged on each side of said panel and extending from the upper and lower corners of the panel to said extensions.

Referring to the drawings, A is the rectangular central panel, having on its inner or rear side a deep rectangular flange or box A', as shown in Figs. 3 and 5.

A' is a transverse cylindrical pocket or tube arranged centrally on the under side of the top flange a of the box A', as shown in Figs.

2 and 5. In the inner edge of the flange a is a rectangular notch or recess a', as shown in Fig. 3.

B are the rectangular horizontal lugs or enlargements arranged at the ends of the side frame, C the upper inclined bars which extend from the upper corners of the central panel to the extensions B, and D the lower reversely-inclined bars extending from the lower corners of the panel to said extensions and connected at their inner and lower ends by a horizontal bar D', arranged underneath the central panel and forming with said lower bars an inverted arch.

e are horizontal ribs or flanges arranged at the lower edge of each extension B on opposite sides thereof, and e' are similar ribs or flanges arranged on each extension between its upper and lower edges. On the upper side of each extension B is arranged a pair of circular bosses f, and between the upper and lower flanges e e' of the extensions are arranged convex bosses f', which are in vertical alinement with the circular bosses f, as shown in Figs. 1 and 2.

What I claim is—

The design for the side frame of a car-truck, substantially as herein shown and described.

Witness my hand this 20th day of February, 1897.

WILLARD F. RICHARDS.
